UNITED STATES PATENT OFFICE

173,009

COMBINED AUTOMOBILE FENDER AND REAR QUARTER PANEL

Harry T. Bannister, Huntington Woods, Mich.,
assignor to Chrysler Corporation, Highland
Park, Mich., a corporation of Delaware

Application June 24, 1953, Serial No. 25,629

Term of patent 7 years

(Cl. D14--6)

To all whom it may concern:

Be it known that I, Harry T. Bannister, a citizen of the United States, residing in the city of Huntington Woods, county of Oakland, and State of Michigan, have invented a new, original, and ornamental Design for a Combined Automobile Fender and Rear Quarter Panel, of which the following is a specification, reference being had to the accompanying drawings, forming part thereof, in which.

Fig. 1 is a side elevational view of a combined automobile fender and rear quarter panel showing my new design;

Fig. 2 is a plan view thereof;

Fig. 3 is a rear elevational view thereof;

Figs. 4, 5, 6 and 7 are sectional views taken on the lines 4—4; 5—5; 6—6 and 7—7, respectively, of Fig. 1; and

Fig. 8 is a rear perspective view thereof on a reduced scale.

The broken line showing in the drawing figures is for illustrative purposes only.

I claim:

The ornamental design for a combined automobile fender and rear quarter panel, substantially as shown and described.
